UNITED STATES PATENT OFFICE

149,190

DESIGN FOR A FINGER RING

Felix P. Kinsley, St. Louis, Mo.

Application February 17, 1947, Serial No. 136,945

Term of patent 14 years

(Cl. D45—10)

To all whom it may concern:

Be it known that I, Felix P. Kinsley, a citizen of the United States, residing at the city of St. Louis, State of Missouri, have invented a new, original, and ornamental Design for Finger Ring, of which the following is a specification, reference being had to the accompanying drawing, forming a part thereof.

Fig. 1 is a perspective view of a finger ring, showing my new design;

Fig. 2 is an edge elevational view of the ring taken from the bottom of Fig. 1;

Fig. 3 is a side elevation of the ring; and

Fig. 4 is an edge elevational view of the ring taken from the top of Fig. 1.

The characteristic feature of my design for a finger ring resides in the angular relationship of

the flat surface of the ring with respect to the axis.

I claim:

The ornamental design for a finger ring, as shown and described.

FELIX P. KINSLEY.
